UNITED STATES PATENT OFFICE.

RALPH THOMPSON, OF MALDEN, MASSACHUSETTS.

REFLECTING SIGNAL.

Application filed January 31, 1927. Serial No. 164,700.

This invention relates to a fixed signal located adjacent to a highway and adapted to be made operative by light projected from a source such as a headlight on a motor vehicle, approaching the signal, the signal reflecting the light back toward the source, and thereby warning an operator on the vehicle.

The object of the invention is to provide a reflecting signal adapted to reflect light in the form of a beam, having a uniform intensity at all portions of its cross-sectional area, said area being substantially equal to the entire area of the reflector, and not interrupted by a dark spot or spots, so that a warning signal of maximum area and efficiency may be reflected.

Of the accompanying drawings forming a part of this specification,—
20 Figure 1 is a front view of a reflecting signal embodying the invention, a portion of the usual glass cover being broken away.

Figure 2 is an edge view of the same.
25 Figure 3 is a fragmentary section on line 3—3 of Figure 1.

Figure 4 is a perspective view of the reflector.
Figure 5 is a section on line 5—5 of Figure 4.

30 Figure 6 is a section on line 6—6 of Figures 1 and 4.

Figure 7 is a front view of the signal, and shows by the unshaded central portion the cross-sectional area of a beam of light reflected by the reflector formed as shown by Figures 4, 5, and 6.

Figures 8 to 13 show a different embodiment of the invention.

Figure 8 is a view similar to Figure 3, 40 fully carried out.

Figure 9 is a perspective view of one of the reflector units shown by Figure 8.

Figure 10 is a section on the plane indicated by the angular line 10—10 of Figure 9.

45 Figure 11 is a fragmentary sectional view, showing portions of two reflector units, a portion of the holder for said units, a portion of the back of the casing, and means securing the inner ends of the units to the holder, and the holder and units to the casing.

Figures 12 and 13 show in perspective, the holder and two reflector units assembled therein.

55 The same reference characters indicate the same parts in all of the figures.

The casing of my improved signal shown by Figures 1, 2 and 3, includes a preferably circular marginal portion 12, having a forwardly facing seat 13, a wall portion 14, 60 projecting inwardly from the marginal portion, and a back 15. The casing is formed with reference to the form of the hereinafter described reflector which chiefly characterizes the invention, the reflector being designed to reflect a beam whose cross-sectional area is substantially equal to the area of the opening in the casing through which the light is reflected, and is of uniform intensity, so that it has no dark or dim portion 70 within its margin.

The seat 13 constitutes a reflector-locating means and imparts a predetermined position of the reflector relative to the light-receiving front portion of the casing. A portion 75 of the reflector is complementary to the locating seat 13, and is preferably an outwardly projecting flange, conforming to the seat 13, and in this instance, composed of flange sections 16 (Figure 4) which may bear on 80 a rubber cushioning ring or gasket 17, interposed between the flange and seat, as shown by Figure 3.

The body of the reflector is composed of a plurality of reflecting ridges, radiating 85 from a common center, which is the center of the reflector. The ridges are preferably of sheet metal provided with highly polished reflecting surfaces, although they may be otherwise adapted to reflect light. The 90 ridges are composed of reflecting faces 18, 18, which meet to form a series of radiating salient outer angles 19. The faces of the ridges meet to form a series of radiating re-entrant inner angles 20, alternating with 95 the salient angles. The faces 18 are of gradually decreasing width from their outer ends to the center of the reflector, so that the angles of one series, preferably the angles 19, are arranged in dished formation, 100 while the angles of the other series, preferably the angles 20, and the center of the reflector are in a common plane. This decreasing width permits the faces 18 of the several ridges to extend from the marginal portion 105 to the center of the reflector, and at the same time, to stand at right angles with each other, as indicated by Figure 6, from end to end, each face being at an angle of forty-five degrees with the plane of the front margin of the reflector casing. The object 110 of this arrangement will be apparent from

the arrows x , y , z in Figure 6. The arrow x indicates a ray extending directly from a source of light, and perpendicular to the plane of the front margin. This ray 5 pings on a face 18 of one ridge, and is reflected across the reentrant angle 20, against the face 18 of the next ridge, as indicated by the arrow y , and again reflected by the last mentioned face back toward the source 10 of light, as indicated by the arrow z . Of course, other direct and reflected rays are at the same time, taking an opposite course. The result is that the faces 18, extending as they do from the outer margin to the center 15 of the reflector, and causing angles of incidence and reflection which are unvarying from end to end, are adapted to receive and reflect light uniformly throughout their entire area, which includes practically the entire area of the reflector. The result is the reflection of what may be called a solid beam of light, or in other words, a well defined beam whose cross-sectional area is substantially equal to the aggregate area of the 20 reflecting faces 18, and has a uniform intensity at all points, so that the reflected beam is particularly adapted to attract attention and effectively impart the warning for which it is intended.

25 The outer ends of the reflecting faces 18 are preferably inclined, as indicated at 18^a (Figure 1), so that the outer end of each ridge formed by said faces, has an outwardly projecting salient angle, said outer ends collectively imparting a star shape to the reflector when viewed from the front. The cross section of the reflected beam of light is therefore star shaped, as shown by Figure 7, in which the unshaded portion 22 shows 30 the illumination provided by the reflected beam.

There is no light reflection outside the outer ends of the reflecting faces 18. The spaces between the inclined outer ends of 45 these faces are preferably filled by triangular plates 23, on the outer edges of which the flange sections 16 are formed. The plates 23 may, for the sake of uniformity, be made of the same material as the faces 18, but 50 their position relative to the direction of the light rays impinging on the reflecting faces is such that they do not reflect the light to any appreciable extent, their function being to prevent the appearance of gaps 55 between the outer ends of the reflecting faces, and to support the flange sections 16. When the reflector is in use, the plates 23 cooperate with the marginal portion of the casing, in producing the shaded marginal portion 60 24, shown by Figure 7.

The casing containing the reflector preferably includes a sheet 25 of the kind of glass usually employed in signals of this character. The glass may be colored and have 65 a rough or pebbled surface. It may be con-

fined against the flange sections 16 of the reflector by a clamping ring 26, secured to the marginal portion 12 by bolts 27, having nuts 28. A rubber gasket 29 may be interposed between the glass and the clamping 70 ring. The opening bounded by the ring 26 is the light-transmitting opening through which direct and reflected rays pass to and from the reflector.

It will be seen that in the described reflector the entire reflecting area is made up of reflecting faces so inclined relative to the direction of impinging light rays that each face is adapted to reflect light to another face, and back toward the source, each face 80 extending continuously from the margin to the center of the reflector, so that the reflector has no portion of appreciable area from which light is not reflected back toward its source.

The ridges constituting the reflector thus far described, may be soldered together at the reentrant angles 20, and the triangular filling plates 23 may be soldered to the outer 90 ends of the ridges, said parts constituting a reflector, the parts of which are inseparably connected. If desired, however, the ridges may be separately formed, so that each constitutes an independent reflector unit which may be separately confined in the described 95 relation to the other ridges or units.

To this end the reflector may be constructed as shown by Figures 8 to 14, inclusive, and as next described.

The reflector includes a pan-shaped sheet 100 metal holder, composed of a flat bottom 30 and an inclined or tapering curb 31, surrounding and projecting outwardly from the bottom and provided with a flange 16^a supported by the seat 13, the pan being 105 formed to enter the casing as shown by Figure 8.

Each ridge or reflector unit including the salient angle 19 and the two reflecting faces 110 18, may be made from a single blank of sheet metal, as shown by Figures 9 and 10, the reflecting faces diverging from the angle 19, and having free edges 18^a (Figure 9) formed to bear on the holder bottom. The faces 18 decrease in width from the outer 115 to the inner end of the ridge, as already described, and are formed at their outer ends to conform to the inclination or taper of the curb 31. Each ridge or unit is therefore provided with acute-angled ends 32 and 33 (Figure 9) which are at opposite ends of the salient angle 19, and are formed to engage confining means with which the bottom and curb of the holder is provided, to confine the units assembled in their predetermined relative positions, the preferred embodiment of the confining means being as next described.

The curb 31 is provided with suitably spaced apart detents 34, which are, in this 130

instance, tongues pressed outward from the sheet metal of the curb and formed to overhang the acute-angled outer ends 33 of the units. The bottom 30 is provided at its center with an orifice 30^a in which is inserted a clamping screw 35, having a frusto-conical head 36, adapted to bear on the acute-angled inner ends 32 of the reflector units. The clamping screw is provided with a nut 37, adapted to be set up against the inner side of the bottom 30, and thus press the screw head against the inner ends of the units. The units may be assembled by inserting them one by one in the holder, the inner end of each unit being located adjacent the orifice 30^a and the outer end engaged with a detent 34. When all the units have been assembled their salient angles 19 radiate from the clamping screw, the head of which overhangs the acute-angled inner ends of the units. The screw is then tightened until the units are firmly secured in their predetermined positions.

To assist the operator in locating the units, I provide the bottom 30 with a series of bosses 39, surrounding the central orifice 30^a and adapted to enter the reentrant inner sides of the units at their inner ends, and cooperate with the detents 34 in causing the units to radiate from the center of the holder. When the units are being assembled, the bottom 30 is preferably in a horizontal position, the clamping screw 35 being removed. When all the units are assembled the screw is tightened.

In Figures 12 and 13 I show the two reflector units first assembled.

The clamping screw 35 is preferably tubular and receives a screw 40, engaging a tapped orifice 41, in the casing back 15, and positively securing the reflector to the casing.

Although the head 36 of the clamping screw forms a non-reflecting surface at the center of the reflector, the area of this surface may be so small that there is no objectionably dark spot at the center of the reflected beam.

The curb 31 may be circular, as indicated by Figure 12, or polygonal, as indicated by Figure 13. The angle of the outer face of the curb is like that of the outer faces of the filling pieces 23, so that the curb does not reflect light upon the reflecting faces of the ridges. The reflector shown by Figures 8 to 13 functions in all respects like the reflector shown by Figures 1 to 7.

I claim:

1. A reflecting signal comprising a casing having a light-transmitting front opening, and a reflector associated with the casing and composed of adjoining reflecting ridges radiating from a common center and having reflecting faces, forming a series of salient angles on the ridges, and a series of re-

entrant angles at the junction of the ridges, said faces decreasing in width from their outer ends inward, and extending continuously from the marginal portion to the center, so that they constitute the entire area 70 of the reflector and are adapted to reflect light from all portions of said area, the arrangement of said faces relative to the casing being such that direct rays from a source of light are reflected from ridge to ridge 75 across the reentrant angles and outward toward the source, so that the reflected light forms an uninterrupted beam, the cross-sectional area of which is equal to the area bounded by the margin of the reflector. 80

2. A reflecting signal as specified by claim 1, one series of angles and the center of the reflector being in a common plane, and the other series having a dished formation.

3. A reflecting signal as specified by claim 1, the reentrant angles and the center of the reflector being in a common plane, which is substantially parallel with, and offset inwardly from, the plane of the reflector margin, the salient angles being inclined inwardly from the margin to the center of the reflector, so that they are assembled in a dished formation. 85

4. A reflecting signal as specified by claim 1, the outer ends of the reflecting faces being inclined to collectively form a star-shaped reflector margin, imparting a star shape to the cross section of the reflected beam. 90

5. A reflecting signal comprising a casing having a light-transmitting front opening and a reflector associated with the casing and including a pan-shaped holder composed of a flat bottom and a curb surrounding and projecting outwardly from the bottom, and a plurality of separately formed reflector units, each of which is a tapering ridge having acute-angled ends and two reflecting faces meeting at a salient angle forming the ridge apex, and having outer edges bearing on the holder bottom body, said faces decreasing in width from end to end, the holder bottom and curb being provided with confining means engaging the acute-angled ends of the units and confining the units against the holder, the arrangement being such that when the units are confined, their salient angles radiate from the center to the curb of the holder, and are located in dished formation. 105

6. A reflecting signal comprising a casing having a light-transmitting front opening, and a reflector associated with the casing and including a pan-shaped holder composed of a flat bottom and a curb surrounding and projecting outwardly from the bottom, and a plurality of separately formed reflector units, each of which is a tapering ridge having acute-angled ends and two reflecting faces meeting at a salient angle forming the ridge apex, and having outer 110

edges bearing on the holder bottom body, said faces decreasing in width from end to end, the holder being provided on its curb with detents engaging the outer ends of 5 the units and at the center of its bottom, with a clamping screw engaging the inner ends of the units, to confine the same against the holder, the arrangement being such that the ridges of the units radiate from the 10 center of the bottom to the curb, and are located in dished formation.

7. A reflecting signal as specified by claim 6, the holder bottom being provided with locating projections engaging the inner ends 15 of the units and locating the same in position to be confined by the clamping screw.

8. A reflecting signal as specified by claim 6, the clamping screw being tubular and receiving a confining screw passing through 20 the center of the holder and engaging the back of the casing.

9. A reflecting signal element composed of a reflector including adjoining reflecting

ridges radiating from a common center and having reflecting faces forming a series of 25 salient angles on the ridges, and a series of reentrant angles at the junction of the ridges, said faces decreasing in width from their outer ends inward and extending continuously from the marginal portion to the 30 center, so that they constitute the entire area of the reflector and are adapted to deflect light from all portions of said area, the arrangement of said faces being such that direct rays from a source of light impinging on the reflector, are reflected from ridge to ridge across the reentrant angles, and outward toward said source, so that the reflected light forms an uninterrupted beam, the cross sectional area of which is equal 40 to the area bounded by the margin of the reflector.

In testimony whereof I have affixed my signature.

RALPH THOMPSON.
